J. D. PEDERSEN.

FIREARM.

APPLICATION FILED MAY 3, 1920.

Patented Mar. 21, 1922.

Inventor:
John D. Pedersen,
By his Atty, J. A. Richards

UNITED STATES PATENT OFFICE.

JOHN D. PEDERSEN, OF JACKSON, WYOMING.

FIREARM.

1,410,266.

Specification of Letters Patent. Patented Mar. 21, 1922.

Application filed May 3, 1920. Serial No. 378,470.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms which are usually designated as small arms, and a principal object of the invention is to furnish an improved form and construction of, and assembling means for the side-plates, or "stocks," of small-arms, and particularly 5 for auto-loading and automatic pistols.

One class of said small-arms to which my present improvements are deemed to be especially applicable, includes auto-loading pistols having a grip-stock, or handle-portion 10 of the frame or receiver of the firearm, which is adapted to receive a magazine and other operating mechanism. An improved auto-loading pistol of this kind is described in my Patent No. 1,348,733, dated Aug. 3, 25 1920, and granted on my copending application (renewal), Serial No. 311,689, filed July 17, 1919, (originally filed July 30, 1915, as Serial No. 42,774), and the improvements herein described and claimed are illustrated 30 in my said patent, but are not claimed therein. Therefore, for convenience of illustration, I have herein illustrated my present improvements as arranged and applied to the particular kind of frame for auto-loading pistols, which is shown in the drawings of said patent, to which reference may be had.

In the accompanying drawing forming a part of this specification, Fig. 1 is a side 40 elevation, and Fig. 2 is a rear-end view of an auto-loading pistol, and these views substantially correspond with Figs. 1 and 2 of said patent; but the lower part of Fig. 2 is herein shown broken away to line X², of 45 Fig. 1, for illustrating certain details.

Fig. 3 is a side elevation of the frame, B, when of a form as shown in Fig. 41 of said patent.

Fig. 4 is a cross-sectional view taken in 50 line X⁴ of Fig. 3.

Fig. 5 is a side view, in section, showing the lower portion of the grip-frame portion

of the frame B in the position thereof shown in Figs. 1 and 3.

Fig. 6 is a detail view for showing the operation of certain parts which are illustrated in Figs. 2 and 5. 55

Fig. 7 is a perspective view of the right-hand stock S', for showing a preferred form and arrangement thereof, as hereinafter 60 more fully explained.

Fig. 8 is a sectional view similar to the lower part of Fig. 2, for further illustrating the operation of the stock-locking pin g, 65

Figs. 9 and 10, are additional detail views for this purpose.

Similar characters designate like parts in all the views.

For herein indicating in a general way, 70 the style and character of a small-arm of the class to which my present improvements are deemed to be especially applicable, there are shown in the drawing a few firearm members not directly involved in the operation of the present invention. For instance, as in said patent, C is a breech action-operating slide; m, a magazine-lock; 8^e is a firing-train actuator, operated by spring 8^e; which also has a further function; F, a 80 trigger; G, a grip-safety member, usually of lever-form, and which is herein shown arranged for being supported on the stock-lock pin g, but which, in practice, may be otherwise supported, or connected; and S⁴, 85 S⁵, are the stocks, or stock-plates, which in this application are designated by S and S', respectively.

The two stocks, (commonly so-called) or handle-plates, S and S', are herein shown as 90 being of the same form, construction and arrangement, except that they are made left-hand and right-hand, respectively; hence, these members may be referred to individually but without choice, as "stock S," and 95 the several duplicated details or features appurtenant thereto, or coactive therewith may be referred to in a similar manner. However, for convenience of identification when this may be required, the right-hand 100 parts and devices are designated in the drawings by the same reference characters as the left-hand ones, but with the addition of a "prime" mark. Thus a description of

either set of such parts will be understood as being applicable to each said set thereof.

That portion of the pistol-frame B which forms the handle part thereof, is herein designated as the grip-frame. This grip-frame, herein designated in a general way by M, is preferably of an open construction, having an interior chamber or space for receiving a magazine and other mechanism, which, 10 preferably, may be substantially such as more fully set forth in said patent. The two side-walls of frame M are indicated (see Fig. 2) by n, n'.

One advantage of the present improvements is that said frame B, may have the side surfaces thereof extending in parallel planes, these coinciding with the side-lines at 2¹, 2², Fig. 4, and be made without any parts or fixed details extending outwardly 20 from said side lines or boundary planes. In Fig. 3, the frame-wall is represented as having therein a large open space M², which divides the grip-wall into two frame-bars 2¹, 2², having on each side of said opening 25 the frame-wall surface 2¹², 2¹³, which constitute the principal seats or faces upon which the stock S is applied; this arrangement is further illustrated in the sectional views Figs. 4 and 5.

30 Upon the inner edges, 2¹², 2¹³, of the left-hand frame-bar 2², (Fig. 3) two pairs of anchorage devices are provided for engaging with coacting devices or portions of the stock S. These anchorage devices of the 35 frame are shown (as a preferable form thereof) as being formed integral with said side-portions, or side-walls, 2¹², 2¹³, of the grip-frame, and as extending inwardly from the lines 2¹², 2¹³, which are the forward and rearward boundaries, respectively, of said opening or space M². The upper pair of said anchorage devices is designated by a², b², and the lower pair by a³, b³, and all are located within the planes of the outer and inner wall 45 frames b⁴, and b⁷.

For effecting the anchorage-engagement each of said anchorage or wall-projections is under-cut, and thus has a face in an inclined position; these faces are designated 50 by a⁴, b⁴, a⁵, b⁵, for said anchorage devices or wall-projections a², b², and a³, b³, respectively. In practice, these anchor-projections are readily and simply formed by cutting away other parts of the wall edge, and thus 55 leaving such anchorage means in the form of projections, or un-removed portions of the side-wall, as will be now readily understood from the drawings by mechanics skilled in the manufacture of this class of firearms.

60 The stock S is shown fitting on, and slideably-supported on the grip-frame M, and is shown provided with a series of pairs of anchorages, of which the faces, s¹, s², s³ and s⁴, are positioned for engaging closely with the 65 coactive frame-faces a⁴, b⁴, a⁵, b⁵, respec-

tively, when the stock is in the fully assembled position thereof shown in Fig. 4. To effect such assembling of the stock on the frame, the stock S, is first placed on the side of the frame in the lowered position indicated by the dotted out line 19, (Fig. 3) at which time said outwardly projecting anchor faces of the stock are each in a position slightly below and disengaged from the coacting anchorage face of the frame-wall; 7 prior to this stock-placing operation, of course, the detainer, or retaining-pin g, should be reciprocated (slid endwise) toward the opposite side of the frame, so as not to prevent the stock S from lying closely upon 80 the frame-wall. Next, the stock S may be slid upwardly on the frame-wall, until brought into said fully assembled position thereof, and during such upwardly sliding movement, each said anchor face of the 85 stock slid under and into engagement with the corresponding anchorage-projection of the frame, thus forming a rigid interlocking system.

For disassembling the "stock" or "stock-plate," S, and removing it from frame B, a reverse operation is followed. The stock-plate retainer,—in this instance, the detainer pin g, is first retracted and the stock then slid down to the dotted-line position 90 thereof. This disengages all of the said anchorage faces of the stock from those of the frame, whereupon the stock is free to be lifted off from the frame-wall. One stock, as S, having been thus removed reciprocately, the detainer, g may then be retracted by a sliding movement to the opposite, or left-hand position thereof, thereby releasing or unlocking the other stock, as S', which may then be drawn down and removed, in 10 like manner as above described. However, either said stock may be removed in advance of the other one, and may be removed and replaced while the other one remains locked in assembled position.

As best shown in Figs. 4 and 7, the stock-plate may have a thickened portion, 19^a, which lies in the plane of side-wall n, when the stock-plate is in assembled position. This portion, or reinforcement, 19^a, is shorter than the frame-opening M², so that when the stock is slid up into final position, the end-face 19^b of said portion 19^a will contact with a wall-face at 2¹ (Fig. 3), and is thus of a length to limit such stock-motion. Similarly when the stock S is slid downwardly to the extent of disengaging the anchorage thereof, the lower-end-face 19^c of said reinforcement contacts with a frame-face at 2², which thus serves as one 115 means for limiting such downward movement, and therein indicating to the user that said anchorages are disengaged; this lowered position of stock S is indicated by the dotted line 19, in Fig. 3. Said reinforce- 120

110

120

125

130

ment 19^a also serves as a convenient base or carrier from which projects one face of each of the aforesaid coactive pairs of the anchorage-faces, as will now be evident from 5 the drawing.

From the foregoing description, it will be seen that below each pair of the said stock-engaging surfaces of the frame B, there is a clearance space so located that 10 each stock may be placed on its proper side of the receiver and moved upward to a position which brings the said pairs of engaging surfaces into contact; and that when said stocks are thus assembled, and 15 the detainer pin g is inserted, this pin, (which is also a pivot-pin in some instances), by projecting on each side of the frame constitutes a lock for securing the stocks in their upward position.

20 Thus the stocks, S, S', are each operably supported, one on each grip-wall, respectively, for reciprocation into engagement with and to disengage from the anchorage faces therefor; and the stock-lock is operably supported for transverse movements in, or on, the frame and is in position for two 25 faces thereof, (as, for instance, the ends of a pin or bolt, as g), each to engage with and lock a stock-plate when this is in the 30 anchorage-face-engaging position thereof.

A particular feature of the holding means whereby the stocks S, S' are prevented from sliding downwardly by their engagement above and against the transverse pin g, is the 35 manner in which this holding-pin is arranged for being slid by hand (or by some suitable instrument in the hand of the operator) toward one side or the other of the frame for thereby unlocking one or the 40 other of said stocks S, S'. This feature will be understood from a comparison of the said details in the several views, but especially in the sectional part of Fig. 2, by comparison with Figs. 1, 5, and 6. Said 45 stock-holding pin g is shown in the medial position thereof in Fig. 2, so that the left-hand end g² of said pin, (or a side or face thereof), comes underneath and locks into place the left-hand stock S, while the right-hand end g³ of said pin extends under the 50 right-hand stock S' and similarly locks this stock upwardly into its frame-engaging and fully assembled position.

For permitting a sliding movement of 55 said stock-retaining member, or pin, this pin is shown, in Figs. 2 and 5, as having midway of the length thereof, a depression or groove g⁴ into which (when in middle position) a pin-retaining device, as for instance the vertically-movable slide or plug 7^b may engage as at g⁵, Fig. 5, for thereby 60 detentively engaging said transverse pin and thus hold this member against accidental displacement in a longitudinal direction. In 65 Fig. 6 said pin-locking slidable member 7^b is

represented as being pushed upwardly or retracted, to a position where it becomes disengaged from said transverse pin, so that said pin may be slid in its supporting-bearing g' (Fig. 2), in either direction, to 70 lock a stock-plate or release the same, as occasion may require.

Said sliding member 7^b, whereby said transverse stock-locking pin is itself detained or locked in a central position, is represented in Figs. 5 and 6 as being the member or detainer, 7^b which, in my aforesaid patent, constitutes a support for a spring, 8^c, which is arranged for actuating an intermediate member 8^c, which in turn is connected with 80 the firing mechanism; but such other features and improvements, as indicated, are not a part of the present invention, and hence are not herein particularly described. However, the said spring 8^c represents one 85 means suitable for actuating said slidable member 7^b for the purpose herein set forth, viz,—of releasably detaining said transverse pin in its central position, (Fig. 2), whereby to positively lock into proper engagement 90 with the frame B, each of the said side-stocks, S, S'.

The anchorage-faces are shown arranged in oppositely-disposed pairs in two ways; first, forward faces a⁶, a⁵, constitute a pair 95 which is oppositely disposed to the rearward faces b⁶, b⁵; second, in the upper pair, the forward face a⁶ is opposite to the rearward face b⁶, and in the lower pair, a⁵, b⁵, the same 100 opposite arrangement.

Said upper pair of frame-faces a⁶, b⁶, are shown located about midway (or slightly higher up) so that this pair engages the upper half of the stock S in a position for effectively retaining this portion of the stock 105 in place, if the stock should be divided (as by a breakage transversely and about midway of its length) into two parts,—as for instance at line X³, Fig. 1. The lower part of said faces, a⁵, b⁵, are shown similarly located in respect of the lower half of said stock-plate S. However, it will be understood that in some instances, only a single pair of the anchorage-faces, as a⁶, b⁶, may 110 be required.

Each said half part of the plate S may be regarded as being individually anchored to the frame, so that each said stock-portion abuts against and thus locates the other as to the longitudinal position thereof in the 120 frame, whether said plate, as S, shall be made in one part or in two parts. This system of stock-retention, as will now be evident, affords security as against the loss of a stock-plate from the breakage thereof, as 125 may readily, and sometimes will result from a blow. This security is especially desirable in the case of relatively long stock-plates,—such, for instance, as herein illustrated,—because of the requirements of the trade that 130

such parts should be non-metallic, and since these plates are made (almost universally) of hard-rubber or analogous molded material, and are therefore peculiarly liable to injury from various causes.

One feature of the pin g and pin-detainer 7^b of the construction shown in Figs. 5, 6 and 8, relates to means for normally actuating said pin toward the stock-locking position thereof, and from either direction by the same actuation means. For this purpose, (in addition to others, which are set forth in said patent), said pin is herein shown having the channel g^4 thereof made of a considerable width, and the detainer 7^b made with a face, g^5 , shaped and positioned to constantly apply an actuating effect to the pin when this is slid either way from the mid-stroke position thereof in Fig. 2. Thus, when applied and actuated as here explained, said detainer 7^b may be described as a combined detainer and actuator for a locking pin, which is a stock-lock. Also, the stock-lock may be said to comprise a stock-engaging lock and a coactive lock-detainer, which may be spring-actuated, or may consist of resilient means arranged for normally actuating said lock toward the stock-locking position or to a mid-stroke position thereof.

In some instances, however, the mechanism may be arranged for detaining the pin g without employing the described additional features. One such arrangement is illustrated in Figs. 9 and 10, in which the pin g has a narrow groove 6, into which the detainer 7^b is pressed by spring 8^e , when that pin is in the mid-stroke position, Fig. 9. When the pin g (Fig. 10) has been pushed to the right-hand, the left-hand stock, S , may be slid down a short distance, so that the lower end, 19^a , thereof engages over the pin-end g^2 , and thus holds the pin in said shifted position, while the plate S is still in effective engagement with the aforesaid anchorage-faces of the frame B . Similarly, said pin g , may be first shifted toward the left-hand, and stock S , drawn down over the retracted end of the pin, but this operation is merely a reversal of the said movements and hence need not be herein illustrated. Thus, as also in Figs. 9, 10, the pin g may be operated to first release, or unlock, either stock-plate, and to permit the removal of and replacement of one or both stock-plates, without the pin itself being removed from its seat, g' , in the frame.

Having thus described my invention, I claim:—

1. In a firearm, in combination, a frame having a grip portion, the grip portion being interiorly chambered and having side walls with open side spaces therein, the side walls being provided with anchorage means on the longitudinal edges thereof adjoining said spaces, and stock plates slidably mov-

able on said side walls having raised portions positionable in said spaces of the side walls provided with anchorage means engageable with the anchorage means of the side walls.

2. In a firearm, in combination, a frame having a grip portion, the grip portion being interiorly chambered and having side walls with open side spaces therein, the side walls being provided with anchorage means on the longitudinal edges thereof adjoining said spaces, and stock plates slidable on said side walls provided with raised inner surface portions conformably engageable in said spaces of the side walls, and said raised surface portions being provided with anchorage means engageable with the anchorage means of the side walls.

3. In a firearm, in combination, a frame having a grip portion, the grip portion being interiorly chambered and having side walls with open side spaces therein, the side walls being provided with anchorage means on the longitudinal edges thereof adjoining said spaces, stock plates slidably movable on said side walls having raised portions provided with anchorage means engageable with the anchorage means of the side walls, and spring pressed pin means for retaining the stock plates in engagement with the anchorage means of the side walls.

4. In a firearm, in combination, a frame having a grip portion, the grip portion being interiorly chambered and having side walls with open side spaces therein, the side walls being provided with anchorage means on the longitudinal edges thereof adjoining said spaces, stock plates slidably movable on said side walls and having raised portions positionable and engageable in said spaces of the side walls provided with anchorage means engageable with the anchorage means of the side walls, and spring pressed pin means for removably retaining the stock plates in engagement with the anchorage means of the side walls.

5. In a firearm, in combination, a frame having a grip portion, the grip portion being interiorly chambered and having side walls with open side spaces therein, the side walls being provided with projecting anchorage means on the longitudinal edges thereof adjoining said spaces, stock plates slidably movable on said side walls and having raised portions positionable and engageable in said spaces of the side walls provided with projecting anchorage means engageable with the projecting anchorage means of the side walls, and spring pressed pin means for removably retaining the stock plates in engagement with the projecting anchorage means of the side walls.

6. In a firearm, in combination, a frame having a grip portion, the grip portion

- being interiorly chambered and having side walls with open side spaces therein, the side walls being provided with anchorage means on the longitudinal edges thereof adjoining said spaces, stock plates slidably movable on said side walls provided with raised inner surface portions conformably engageable in said spaces of the side walls, said raised surface portions being provided with anchorage means engageable with the anchorage means of the side walls, and spring pressed pin means for removably retaining the stock plates in engagement with the anchorage means of the side walls.
7. In a firearm, in combination, a frame having a grip portion, the grip portion being interiorly chambered and having side walls with open side spaces therein, the side walls being provided with anchorage means on the longitudinal edges thereof adjoining said spaces, stock plates slidably movable on said side walls provided with raised inner surface portions conformably engageable in said spaces of the side walls, said raised surface portions being provided with anchorage means engageable with the anchorage means of the side walls, and slidable pin means engageable with said frame and with edge portions of the stock plates and spring pressed for removably retaining the same in engagement with said frame and edge portions.
8. In a firearm having an open-side grip-frame, in combination, a stock-plate fitting and slidably supported on the frame and having a reinforcement portion positioned within the open-side of the frame; a series of pairs of coactive anchorage-faces of which two said pairs are on the forward side of said reinforcement, and of which one said face of each pair is on the frame and the other said face is on said reinforcement, and said reinforcement being also of a length for limiting the movement of the stock-plate from an anchorage-engaging position to an anchorage-disengaging position, and means retractably supported in the frame for releasably locking said stock-plate in the anchorage-engaging position thereof.
9. In a firearm having an open-side grip-frame, in combination, a stock-plate fitting and slidably supported on the frame and having a reinforcement portion positioned within the open-side of the frame; a series of pairs of coactive anchorage-faces of which one said face of each pair is on the frame and the other said face is on said reinforcement, and said reinforcement being also of a length for limiting the movement of the stock-plate toward the anchorage-engaging position thereof; and a stock-plate detainer operably supported in the frame in position for releasably locking said stock-plate in the anchorage-engaging position thereof, and retractable for unlocking said stock-plate.
10. In a firearm having an open-side grip-frame, in combination, two stock-plates fitting and slidably supported on opposite side-walls respectively, of the frame, each said stock-plate having a reinforcement portion positioned within an open-side of the frame; and there being for each said reinforcement a series of pairs of coactive anchorage-faces of which one said face of each pair is on the frame and the other said face is on a reinforcement, and a stock-plate detainer operably supported in the frame in position for releasably locking both of said stock-plates in the anchorage-engaging positions thereof, and retractable in a direction for unlocking one stock-plate while continuing to lock the other plate.
11. In a firearm, in combination, a frame having the grip thereof provided with anchorage faces positioned within the side planes of the frame; stock-plates having anchorage-engaging means and slidable on the grip to engage with and to disengage from said anchorage faces; a stock-locking pin slidably supported transversely in the frame in position for the ends thereof, each to engage and lock a stock-plate when this is in said anchorage-face-engaging position, said pin being slidable in one direction out of engagement with one said stock-plate, and in the opposite direction out of engagement with the other said stock-plate.
12. In a firearm, in combination, a frame having the grip thereof provided with anchorage faces positioned within the side planes of the frame, and arranged in oppositely-disposed pairs; stock-plates having anchorage-face engaging means and slidable to engage with and to disengage from said anchorage faces; a stock-lock supported on the frame in position for the ends thereof, each to engage and lock a stock-plate when this is in said anchorage-face-engaging position, said lock being operable in one direction out of engagement with one said stock-plate, and in the opposite direction out of engagement with the other said stock-plate; a lock detainer in position for normally retaining said lock in the stock-locking position thereof, and, means for yieldingly holding said detainer in engagement with the stock-lock.
13. In a firearm, in combination, a frame having the grip thereof provided with anchorage faces positioned within the side planes of the frame; and arranged in oppositely-disposed pairs; a stock-plate on the grip and slidable to engage with and to disengage from said anchorage faces; a stock-lock reciprocatable in the frame to engage with and to disengage from the stock-plate when this is in anchorage-face-engag-

ing position; and a lock detainer, in position for a detentive engagement with said lock when this is in the stock-locking position thereof.

5 14. In a firearm, in combination, a frame having the grip thereof provided with a plurality of pairs of anchorage faces positioned within the side planes of the frame; a stock-plate on the grip and slideable to engage and to disengage said pairs of anchorage faces; a stock-lock supported for movement transversely of the frame and in position to engage and lock the stock-plate when this is in said anchorage-face-engaging position; a movably supported lock detainer, in position for detentively engaging said lock when this is in the stock-locking position thereof; and, a spring in position for yieldingly holding said detainer into engagement with the stock-lock.

20 15. In a firearm, in combination, a frame having the grip thereof provided with anchorage faces positioned within the side

planes of the frame, and arranged in oppositely-disposed pairs; a pair of stock-plates on the grip and slideable to engage and to disengage said anchorage faces; a stock-locking pin slidably supported transversely in the frame in position for the ends thereof each to engage and lock a stock-plate when this is in said anchorage-face-engaging position, said pin being slideable in one direction out of engagement with one said stock-plate, and in the opposite direction out of engagement with the other said stock-plate; a movably supported pin detainer, in position for normally engaging said pin when this is in the stock-locking position thereof, and a spring in position for yieldingly holding said detainer into engagement with the stock-lock.
